ATTORNEYS

UNITED STATES PATENT OFFICE.

FLOYD WILLIAM SCHOOLEY, OF CHICAGO, ILLINOIS.

CHECK HOLDER AND PUNCH.

Application filed November 24, 1922. Serial No. 603,015.

To all whom it may concern:

Be it known that I, FLOYD WILLIAM SCHOOLEY, a citizen of the United States, and a resident of Chicago, in the county 5 of Cook and State of Illinois, have invented a new and useful Improvement in Check Holders and Punches.

My invention relates to improvements in check holder and punch, and it consists 10 in the combinations, constructions, and arrangements herein described and claimed.

An object of my invention is to provide a check holder and punch which is fashioned from a single piece of metal, and which is 15 adapted to carry the pad of checks and also punch the check when desired.

A further object is to provide a device of 20 the type described which has means for determining the movement of the punching means, this means also acting as a stop for the check to be punched.

A further object is to provide a device 25 of the type described which has an integral clip for securing the device to a belt or the like.

A further object is to provide a device 30 of the type described which makes use of means for securing the device to an apron or the like.

A further object is to provide a device 35 of the type described which is simple in construction, durable, and efficient for the purpose intended, and which is not likely to easily get out of order.

Other objects and advantages will appear 40 in the following specification, and the novel features of the invention will be particularly pointed out in the appended claim.

My invention is illustrated in the accompanying drawings forming part of this application, in which—

Figure 1 is a plan view of the device,

Figure 2 is a side elevation of the device,

Figure 3 is a perspective view of the device as shown secured to a belt, and

Figure 4 is a perspective view of the attachment which is adapted to carry the device and to be secured to an apron or the like.

In carrying out my invention, I provide a 50 single piece of metal which is cut out so as to form a supporting base 1, and a ticket supporting member 2. It will be noted that the member 2 is bent back beneath the base 1 and extends a slight distance beyond the end of the base. The base is provided with

upwardly extending sides 3 and upwardly extending lugs 4 which are adapted to receive the ticket pad 5 and to hold it against movement. Inwardly extending prongs 6 60 are carried by the sides 3 and are embedded in the pad 5 so as to prevent the removal of the pad from the base 1. It will be seen from this construction that the base 1 is adapted to securely hold the pad 5 when 65 the pad is once disposed thereon.

The ticket supporting member 2 is adapted to be moved toward or away from the base 1. The lug 7 is stamped out of the member 2 and is adapted to provide a stop 70 for the movement of the member 2, and to also provide a stop for a ticket 11, whereby the ticket is automatically positioned with respect to the device. As clearly shown in Figures 1 and 2, a portion of the base 1 is 75 extended and is provided with a triangular punching member 10 which is aligned with the opening 8 and which is adapted to enter the opening when the member 2 is moved toward the base 1. When the punching member 10 is moved into the opening 8, it is adapted to remove the portion of a check 11 which has previously been disposed between the member 2 and the base 1. The lug 7 not only determines the movement of 80 the member 2 but also provides a stop to the ticket 11.

The member 2 has a clip-shaped portion 12 stamped out therefrom, this clip being adapted to secure the device to a belt 13 or 90 the like, (see Figure 3). In case the person using the device is not equipped with a belt but has an apron or other like garment, the device may be secured to a supporting base 14, (see Figure 4). This base has arms 95 15 which have prongs 16 that are adapted to enter the openings 17 when the prongs 15 are swung into closed position. The body portion 18 is disposed on one side of the garment 19 and the arms 15 are disposed 100 on the opposite side, whereby the device is secured to the garment. The body portion 18 has a strip 20 cut therefrom which is bent outwardly so as to provide an opening 21. The strip 20 receives the clip 12, whereby 105 the device is removably secured to the supporting base 14.

From the foregoing description of the various parts of the device, the operation thereof will be readily understood. In securing a pad 5 to the device, the open end of the pad is inserted between the prongs 6 110

2
and the lugs 4, and is moved into the position shown in Figure 2. In this manner the prongs 6 extend into the head portion of the pad 5 and prevent the pad 5 from movement with respect to the base 1. When the ticket is desired to be punched, it is first removed from the pad 5 and is placed between the base 1 and the member 2 so that the end thereof abuts the lug 7. The number on the ticket 6 which is desired to be punched out is brought into alignment with the punch 10. The operator now moves the member 2 toward the base 1, whereupon the punch 10 will enter the opening 8 and will sever the portion of the ticket which previously covered the opening. In this manner the ticket is punched at the desired place. The lug 7 prevents the ticket from being moved inwardly to too great a distance and also prevents the member 2 from moving into engagement with the base 1. The tickets can be punched in the manner heretofore described and when the pad 5 has

been used, a new pad can be substituted for the old one.

25 The clip 12 permits the device to be readily carried on the belt or pocket of a person, whereby the device is within handy reach. As heretofore stated, if desired, the supporting base 14 may be used and the device secured thereto by disposing the clip 12 over the strip 20. The device is very cheap to manufacture since it is made from a single piece of material which is bent and cut into the shape shown in the drawings. 30 35

I claim:

A check punch comprising a frame having a cutter, a ticket holder having an opening therein adapted to receive the cutter whereby the cutter is adapted to punch a ticket, 40 a stop carried by said ticket holder for positioning the ticket with respect to the cutter and for limiting the movement of the cutter.

FLOYD WILLIAM SCHOOLEY.
